Des. 205,878
Patented Sept. 27, 1966

205,878

CARRYING CASE FOR TELEPHONIC COMMUNICATIONS APPARATUS

Frederick G. Buhrendorf, Colts Neck, N.J., Henry Dreyfuss, South Pasadena, Calif., and Oskar Loesme, Lin-croft, N.J., assignors to Bell Telephone Laboratories, Incorporated, New York, N.Y., a corporation of New York

Filed Sept. 20, 1965, Ser. No. 87,068

Term of patent 14 years

(Cl. D87—5)

FIG. 1

FIG. 2

FIG. 3

FIG. 4

FIG. 5

FIG. 1 is a front elevational view of a carrying case for telephonic communications apparatus showing our new design; the rear, not shown, is similar in appearance but also includes four plain, round mounting feet;

FIG. 2 is a top plan view thereof;

FIG. 3 is a right-side elevation thereof;

FIG. 4 is a perspective view thereof; and

FIG. 5 is a perspective view thereof, showing the case in open condition.

We claim:

The ornamental design for a carrying case for telephonic communications apparatus, substantially as shown and described.
